UNITED STATES PATENT OFFICE.

CHARLES HAMMER, OF BROOKLYN, NEW YORK.

BOTTLE OR JAR CLOSURE.

1,160,596.

Specification of Letters Patent. Patented Nov. 16, 1915.

Application filed August 8, 1912. Serial No. 714,141.

To all whom it may concern:

Be it known that I, CHARLES HAMMER, a citizen of the United States, residing at Brooklyn, in the county of Kings and State 5 of New York, have invented a new and useful Bottle or Jar Closure, of which the following is a specification.

This invention relates generally to bottle or jar closures, and particularly to a closure 10 for use with a jar or bottle having separated, inclined threads in place of a single continuous thread.

The principal object of the invention is to provide an improved form of in-pressed 15 rib or projection to engage the inclined threads of the jar or bottle.

With the foregoing and other objects in view which will appear as the description 20 proceeds, the invention resides in the combination and arrangement of parts and in the details of construction hereinafter described and claimed, it being understood that changes in the precise embodiment of invention herein disclosed can be made within the 25 scope of what is claimed without departing from the spirit of the invention.

In the accompanying drawing forming part 30 of this specification, Figure 1 is a side elevation of a jar or bottle having a cap provided with the improvements of the present invention; Fig. 2 is a side elevation of the upper end of the jar or bottle showing the inclined threads; Fig. 3 is a vertical section through the upper end of the bottle neck and 35 cap; Fig. 4 is a section through the cap on the line 4—4 of Fig. 3 showing the shape of the in-pressed projection; Fig. 5 is an enlarged view showing in perspective one of the in-pressed ribs or notches.

40 Like reference numerals indicate corresponding parts in the different figures of the drawing.

The reference numeral 1 indicates the neck of a jar or bottle and 2 an annular rib thereon. Extending upward from the rib 2 is 45 a plurality of inclined separated threads 3. The bottle cap 4 is formed with a top 5 and a depending annular flange 6. The flange 6 is formed preferably with series of outer 50 punched corrugations 7 and a plurality of

in-pressed ribs or projections 8. I also provide the top 5 with a stiffening rib, shown clearly in Fig. 3, in the top of the same, this rib being punched so as to extend downward from the inner face of the top. 55

As shown clearly in Fig. 4, each of the projections 8 has a shallow end 9 and a deep end 10, and, as indicated in Figs. 1 and 5, each rib is narrow at the end 9 and widens or flares outwardly toward the end 10. The 60 lower edge of each notch 8 is parallel with the rolled or beaded edge 12 of the flange 6, and the upper edge 14 of each rib is upwardly inclined, so as to be parallel with the pitch of the separated threads 3. By forming 65 the notches 8 in the manner indicated, with one end shallow and the other end, deep, and the lower edge parallel with the lower edge of the flange, and the upper edge parallel with the pitch of the threads, the 70 notch is not only strong and durable in construction, but it is adapted to be readily engaged and screwed down into position on the separated threads.

The cap is applied to the bottle in the 75 usual manner, so that the ribs 8 extend in between the groups of threads 3, after which it is only necessary to turn the cap to cause the ribs of the cap to engage the ribs or threads of the jar or bottle. 80

As illustrated particularly in Fig. 2, the threads 3 are arranged in pairs, and the members of each pair are placed one above the other and are of substantially the same length or coextensive with each other. When 85 the cap is screwed on, each one of the projections 8 will be engaged by one pair of threads 3, and will pass between the members of the pair; but will bind principally against the lower portion of the uppermost to hold 90 the cap tight on the jar or bottle. This is because the upper portion 14 of each projection is inclined to correspond to the pitch of the threads; while the lower portions of the projections are preferably formed so as to 95 lie quite close to the rolled edge 12 over the greater part of their lengths from the ends 9 to the ends 10, the latter ends being made wider than the former mainly for the purpose of giving the necessary slope to the 100

projections without unduly spacing or separating the ends 10 from the rolled edge 12. The utility of this construction resides in the fact that a set of projections having the 5 shape and position just described are capable of enabling the rolled edge 12 to resist buckling of the flange and other deformations of the cap to best advantage. For example, when the cap is made to engage the threads 3 10 securely, the downward pressure of the upper threads 3 on the upper portions 14 is transmitted to the lower portions of the projections and by such lower portions is given more of an outward direction. If the lower 15 portions were not arranged close to the edge 12 over nearly the whole length of the projections, this outward component of the pressure in question might take effect all at one point and produce a sharp bend or 20 shoulder in the rolled edge. But by the arrangement above set forth, such a concentration of the deforming stress is prevented, and the pressure is exerted across nearly the whole length of the lower portion of each 25 projection 8 upon a considerable section of the length of the rolled edge, and the liability of buckling or the like is consequently obviated. The same desirable effect might be obtained, though in smaller degree, by 30 making the lower portions of the projections parallel with the upper portions 14, and causing the ends 9 to indent the rolled edge slightly; whereby the greater part of the 35 lengths of the lower portions would still be close enough to the rolled edge to insure a good reinforcing action by the edge 12. It is only necessary that the slope of the projections be not too great; so as not to space the ends 10 too far from the edge 12.

40 While I prefer to use the cap shown and described herein along with the type of threads shown particularly in Fig. 2, I wish to state that my cap may be employed with other designs of threads as well; particularly when such other designs of threads involve a plurality of pairs of threads so arranged as to receive the projections 8 between the members of the pairs.

What is claimed is:

- 50 1. A cap comprising a top and a flange, the flange having inwardly extending ribs or projections, each of which is deep at one end and shallow at the other end, the upper edge of each rib being downwardly inclined 55 with relation to the top of the cap.
2. A cap having inwardly extending ribs, each of which is narrow and shallow at one end and wide and deep at the other end, the upper edge of each rib being downwardly inclined 60 with relation to the top of the cap.
3. The combination with a jar or bottle having a plurality of separated inclined threads, of a bottle cap comprising a top and flange, said flange having therein a plu-

rality of inwardly extending ribs, each being narrow and shallow at one end and wide and deep at the other end, the lower edge of each rib being parallel with the lower edge of the flange and the upper edge of each rib being parallel with the pitch of the 65 separated threads and downwardly inclined with relation to the top of the cap, substantially as described.

4. A cap having a flange provided with a strengthened edge, said flange having corrugations terminating short of the edge and one or more inwardly extending projections located between the edge and the corrugations, said projections being relatively narrow and shallow at one end and relatively 75 wide and deep at the other end, the lower edge of the projections being substantially parallel with the strengthened edge and the upper edge being inclined thereto, the relatively wide ends of the projections extending 80 entirely across the space between the corrugations and said strengthened edge.

5. The combination with a storage vessel having a mouth and a plurality of pairs of inclined, separated overlapping threads adjacent said mouth, of a closure comprising a top and a flange, and having a plurality of inwardly extending projections on said flange, said projections having inclined upper portions, and being located at the same 95 distance from the top, said projections also being adapted to be received between the threads of each pair to secure the closure to the vessel.

6. A storage vessel having a mouth and a 100 plurality of pairs of inclined, separated threads arranged at intervals around said mouth, the threads of each pair being placed side by side and being substantially coextensive with each other.

7. A closure for a storage vessel comprising a top and a flange, the latter having a strengthened edge and one or more projections on its inner face, said projections extending circumferentially of the flange, and having their sides toward the top inclined with respect to the top, and their opposite sides placed relatively close to the strengthened edge over nearly the whole length of 105 said opposite sides.

8. A closure for a storage vessel comprising a top and a flange, the latter having a strengthened edge and one or more projections on its inner face, said projections extending circumferentially of the flange, and having their sides toward the top inclined with respect to the top, and their opposite sides arranged relatively close to and parallel with the strengthened edge over 110 nearly the whole length of said projections.

9. A closure for a storage vessel, comprising a top and a flange, the latter having its edge turned over in order to strengthen the 115

same, and having one or more projections on its inner face, said projections each beginning at said turned edge and extending circumferentially of the flange in an inclined 5 direction toward the top, and being in close proximity to the rolled edge over substantially their entire length.

In testimony that I claim the foregoing as my own, I have hereto affixed my signature in the presence of two witnesses.

CHARLES HAMMER.
